DEVICE FOR HOLDING STOCKINGS ON FORMS

Original Filed May 7, 1924

Patented Apr. 17, 1928.

UNITED STATES PATENT OFFICE.

EDWARD J. ZIOCK, OF ROCKFORD, ILLINOIS.

DEVICE FOR HOLDING STOCKINGS ON FORMS.

Original application filed May 7, 1924, Serial No. 711,565. Patent No. 1,623,080, dated April 5, 1927.
 Divided and this application filed September 20, 1924. Serial No. 738,756.

This invention, a division of my application Serial No. 711,565 filed May 7, 1924, relates to means for holding any knitted article, such for example as a stocking, on a board or form while it is being dried or subjected to any liquid treatment or other processing operation.

The primary purpose of the present invention is to provide improved means for holding a stocking or the like on a form so that the stocking will not draw or creep on the form during any processing or finishing operation.

I have also aimed to hold a stocking by means of clamping elements so constructed and arranged that the entire fabric will be exposed and uniformly subjected to the action of any liquid or other agents used in treating, dyeing or drying processes. To this end I employ clamping elements in the form of small gage wire strips mounted to clamp the outer sides of a stocking from edge to edge of the form. The clamping engagement is such as to hold the fabric under uniform tension without injury and without obstructing the admission of dye or other liquids to the clamped parts of the fabric.

Still another object is to provide a stocking form and holding means therefor adapted to be mounted on a traveling carrier and to provide means for automatically actuating the stocking clamping means at predetermined times as for example by motion derived from the travel of the carrier.

Other objects and attendant advantages will be appreciated by those skilled in this art as the invention becomes better understood by reference to the following description when considered in connection with the accompanying drawings, in which

Figure 1, is a side elevation of a stocking form and holding or clamping means embodying my invention;

Fig. 2, is an enlarged side elevation of the clamp-equipped end of the form mounted on a track;

Fig. 3, is an end view of the parts shown in Fig. 1, partly in vertical section;

Figs. 4 and 5, are sections taken substantially on the lines 4-4 and 5-5 respectively of Fig. 2; and

Fig. 6, is a top view of one of the clamping elements.

The device disclosed herein may be used

in conjunction with any apparatus wherein it is desired to hold each knitted article on an individual form while drying or subjecting the knitted article to any processing or finishing operation. My invention is not necessarily confined to the holding of knitted articles such as stockings since it will be evident that the form per se might be shaped to hold knitted or fabric articles of other descriptions. The device herein disclosed for purpose of illustration is designed for use in apparatus of the general character disclosed in my parent application above mentioned and is intended therefore to be used on a traveling carrier which carries the forms from station to station at which one or more operations may be performed on the stockings.

Referring more particularly to the drawings, I have shown in Figs. 2 and 3 a track 75 on which a carrier in the form of a roller chain 9 is adapted to travel. In this particular instance two opposed track members 8 will be employed with a roller chain on each, connected by crossbars 11. To these 80 crossbars the stocking holding forms are attached, in this instance so as to extend outwardly from the carrier perpendicular thereto.

The boards or forms (only one of which is shown) are preferably of aluminum, shaped to conform to the knitted shape of the article or to any given shape which it is desired the article shall conform to when finished, except that the form is comparatively flat and tapered at its edges to a sharp but rounded edge so that the fabric of the stocking will be held extended or taut without appreciable stretching. A stocking will be drawn on to each form to a predetermined length and held at such length by a clamping or holding device embodying my invention.

In the present case the stocking form 12 is carried in an upright position by a bracket 13 the base 13' of which is bolted to one of the carrier chain cross-bars 11. To each side of the form is fixed above the form-supporting bracket 13, a clamp-supporting part 14 the upper portion 15 of which is convex on its outer face and serves as a platen against which the stocking fabric is adapted to be clamped. The converging taper at each end of the parts 15 is continued on the interposed form plate providing tapered edges on the 110

form as shown in Fig. 4. The hem of the stocking will be drawn down over this platen portion and clamped thereagainst by small gage wire clamping members 16. These are carried by clamping levers 17 and 18 in the form of yokes pivotally mounted at 19 on the clamp-supporting parts 14 so as to swing into and out of clamping position. The clamping levers are adapted to be oscillated by a thrust rod or plunger 21 vertically slidable in the bracket 13 and connected by means of a cross-head 22 and links 23 to said levers. A coiled compression spring 24 acting against the lower end of the plunger 21 constantly urges the latter upwardly to transmit clamping pressure and hold the clamping wires yieldingly against the fabric with sufficient tension to prevent the fabric from drawing, creeping or being otherwise displaced on the form. It will be observed that the clamping wires conform to the peripheral shape of the stocking form and engage the fabric from edge to edge thereon. In the preferred form of my invention the yoke-shaped levers 17 and 18 are of greater width than the stocking form as plainly shown in Fig. 4 so that the wire clamping elements are supported from beyond the edges of said form and are therefore adapted to have uniform contact with the stocking fabric from edge to edge. This insures against any uneven pulling or drawing of the fabric which might result if it is not held from edge to edge of the form. Because of the small diameter of the wire clamping members and of the comparatively small pressure required to hold the fabric due to the fact that the stocking is entirely embraced by said members, liquids used in treating the stocking will not be excluded to any appreciable extent. For example, in the case of dyeing, the dye will not be excluded by the wire clamping members.

Suitable means may be provided for releasing the clamping wires, such for example as one or more stationary cams 25 which are adapted to be engaged by rollers 26 carried by the plunger 21 at the outer side of the bracket 13 for retracting the plunger against the pressure of the spring 24 and thus withdrawing the clamping wires from the stocking. The clamps will be held in the inoperative position by the stationary cam structure until the stocking has been removed from the form and another replaced, whereupon the rollers 26 will be released by riding out from under the cams, thereby permitting the spring 24 to actuate the clamping wires and grip the stocking as described. It should be understood that my invention is not confined to the use of automatic means for applying and releasing the clamping pressure. These movements might be imparted manually as by an operator grasping the projecting rollers 26 or the equivalent

or by the application of suitable mechanical means. The automatic means for releasing the clamping wires is desirable when a traveling carrier is used for moving the forms from station to station; and in the preferred embodiment the clamping and releasing movements are either initially imparted or are actuated by motion of the carrier. In this manner each clamping device is positively and uniformly operated and the least amount of manual labor is involved in boarding and removing the stockings.

It is believed that the foregoing conveys a clear understanding of the objects prefaced above and while I have illustrated but a single working embodiment it should be understood that changes might be made in details of construction without departing from the spirit and scope of the invention as expressed in the appended claims, in which—

I claim:

1. A stocking holding and clamping device comprising a stocking form, a flexible wire clamping element for each side of the form arranged to be moved into and out of clamping engagement with the form for holding a stocking thereon, each wire element being arranged readily to conform itself to the shape of the surface engaged thereby by the entire width of the stocking and being arranged to extend crosswise of the form beyond the opposite edges thereof whereby the two elements completely encompass the form, and spring means for operating said wire clamping elements normally toward engagement with the form with sufficient pressure to cause the elements to conform themselves in uniform contact with said form.

2. A stocking holding and clamping device comprising a stocking form, and a wire clamping element for each side of the form adapted to be moved into and out of clamping engagement with a stocking thereon, each wire element being of a small gage and extending crosswise of the form and beyond the edges thereof.

3. A stocking holding and clamping device comprising a stocking form and a clamping element for each side of the form comprising a flexible wire serving as a narrow engaging member, said wire by reason of its flexibility being arranged to conform itself to the shape of the form to give uniform pressure on the stocking and being arranged to engage a narrow strip of stocking throughout the width of the form so that the dye is permitted to permeate the stocking, and means for moving the clamping wires into and out of clamping engagement with a stocking on the form.

4. A stocking holding and clamping device having, in combination, a stocking form, a clamping member for each side of the form adapted to be moved into and out of clamp-

ing position to engage a stocking on the form, each member comprising a flexible wire extending crosswise of the form and supported beyond the edges thereof so that the wire is free to conform to the outside shape of the form from edge to edge, and a support for the wire, and means for moving the clamping members into and out of clamping engagement with the stocking on the form.

5. A stocking holding and clamping device having in combination, a stocking form, a clamping member for each side of the form adapted to be moved into and out of clamping position to engage and hold a

stocking on the form, each member comprising a flexible wire extending crosswise of the form and supported beyond the edges thereof so that the wire is free to conform to the outside shape of the form from edge to edge and about the edges, and a support for each wire, said supports being arranged to overlap when in clamping position whereby the wires completely encompass the form to clamp the stocking thereto throughout its entire circumference, and means for moving the clamping members into and out of clamping engagement with the stocking on the form.

EDWARD J. ZIOCK.
